INVENTOR, BY
Charles H. Woodward Atty.

UNITED STATES PATENT OFFICE.

DANIEL A. DICKINSON, OF ST. PAUL, MINNESOTA.

STEAM OR HOT-WATER GENERATOR.

SPECIFICATION forming part of Letters Patent No. 473,109, dated April 19, 1892.

Application filed September 18, 1891. Serial No. 406,053. (No model.)

To all whom it may concern:

Be it known that I, DANIEL A. DICKINSON, a citizen of the United States, residing at St. Paul, in the county of Ramsey and State of Minnesota, have invented certain new and useful Improvements in Steam or Hot-Water Generators, of which the following is a specification.

This invention relates to steam or hot-water generators; and it consists in the construction, combination, and arrangement of parts, as hereinafter shown and described, and specifically pointed out in the claims.

In the drawings, Figure 1 is a sectional elevation. Fig. 2 is a plan view on the line xx of Fig. 1. Fig. 3 is a sectional detail illustrating the modifications necessary to adapt the generator to a hot-water system.

This invention is an improvement on my former patents on generators, No. 356,103, dated January 18, 1887; No. 390,461, dated October 2, 1888; No. 431,037, dated July 1, 1890; No. 449,150, dated March 31, 1891, and No. 454,459, dated June 22, 1891.

25 A represents the ash-pit casing, upon top of which the fire-pot B' rests, the latter formed with double walls, so as to permit of a water-space therein, as shown.

The body of the generator above the fire-pot is formed of a series of hollow horizontal sections of different diameters and arranged in alternating order, as shown. The lowermost section D' is formed smaller than the next section D² above it, and is connected at a number of points by joints E' to corresponding joints E², rising from the fire-pot B'. The section D' is joined to the section D² by joints E³ E⁴, while the next section above D³ is joined to the section D² by joints E⁵ E⁶ in the same manner, and so on for as many sections as may be required. Generally three of the sections D' D² D³, besides the dome-section D⁴, will be all that will be required; but a greater or lesser number may be employed, as circumstances may require. The dome-section D⁴ is connected to section D³ by joints E⁷ E⁸ in the same manner as the sections D' D² D³ are connected to each other and to the fire-pot B'. The upper sides or inclosing walls of each of the several hollow sections D' D² D³ and of the fire-pot B' are made to gradually turn upward, as shown at E² E⁴ E⁶

E⁸, in either curved or inclined planes, and to develop into and form openings and conduits from the fire-pot and from each of such sections, respectively, to meet and connect with corresponding openings and parts E' E³ E⁵ E⁷ in the under sides of the sections immediately above, the parts thus brought in contact being bolted together, as hereinafter stated.

In the structure represented in the drawings it is supposed that the tops of each of said sections and of the fire-pot are thus formed into three of these inclined elevations and connections, which are partially shown in the drawings; but more or less than three may be formed in each section or part, as the size and capacity of the boiler may render desirable. This upward inclination and elevation of the parts E² E⁴ E⁶ E⁸ may include the whole or greater part of the upper sides or walls of the several sections and fire-pot B', so that the upward tendency of the steam and hot water may not be opposed by any considerable area of horizontal surfaces in the upper sides or parts of such sections or inclosures.

Each of the large sections D² and also the dome-section D⁴, will be provided with central openings D⁶ D⁷ through which the smoke, gases, and other products of the combustion pass to the smoke-flue.

The course of the products of the combustion is shown by the arrows in Fig. 1, being in a zigzag form upward from the fire-pot, striking the under side of and passing around the smaller section D', thence inward against the under side of the next section D², and thence inward and through the central opening D⁶ in the larger section D², thence upward against the under side of the next section D³, and thence outward and around the next section D³, and so on out through the central opening D' in the dome-section, thus passing over a very large area of the different sections in its passage from the fire-pot to the exit-flues. The dome-section D⁴ and also the section D² are each provided with downwardly-extending hollow projections D⁸ D⁹, the projection D⁹ resting above but not quite touching the flange e of the fire-pot B', while the projection D⁸ reaches nearly to but does not quite touch the upper surface of the

section D², as shown, the two projections forming a water-jacket around the generator. At one side openings b' b² are left through the projections D⁸ D⁹ and covered by a door b³ 5 to form inlets to the interior of the generator to admit brooms or brushes for removing ashes, soot, &c., from the sections. The frame b⁴ of the doors will preferably be formed in one piece with the door b⁵, by which the fuel 10 is supplied to the fire-pot to save expense and for the convenience of the operator.

Across each of the sections D' D² D³, opposite to and within the joints connecting them, are partitions F', with their ends F² projecting outward toward and nearly to the outer inclosing wall of the water-chambers within the walls of the sections, so that contracted spaces only are left for the water to pass outside of the partitions. The adjacent upper 15 and lower edges of the partitions F' of the different sections come flush with the outer edge of the joints by which they are united and are adapted to be turned off true with them, so that the partitions will be continuous 20 throughout the whole generator, as shown in Fig. 1.

The fire-pot is supplied with tubular projections B², corresponding in location with the connections between the sections D' D² D³ 30 and leading downward from the joints E' E², as shown, and with the return connections entering them at d. These projections B² are supplied with cross-partitions F³, as shown, corresponding with the partitions F', so as to 35 be continuous downward therefrom.

By means of each of the series or sets of partitions F' F² F³ two continuous compartments a' a² are formed through the several sections and joints from the fire-pot to the 40 steam-dome or upper section. Each of the inner of these compartments a² receives and carries upward steam or heated water from the fire-pot and from the several horizontal sections, while the return-water to supply the 45 fire-pot and the several horizontal sections is carried back to them through the outer compartment a'. In a steam-generator this return or supply current is always downward from the steam-dome through the compartments a', each section drawing its proper supply 50 therefrom around the ends or wings F² of the partitions F' and the fire-pot drawing its supply from the bottom, the current passing down outside and under the bottom of the 55 partition F³.

When used as a hot-water heater the partitions F³ in the fire-pot may be dispensed with and the partitions F' in section D' turned inward, as at h', Fig. 3, so as to direct 60 the upward flow of the water from the fire-pot into the outer compartments a'. When so used, (as a hot-water heater,) the current of the return-water supplying the several sections, entering the boiler at d', flows upward 65 into the compartments a', which will be closed at the top of the upper section, as shown at h² in Fig. 3. The water then flows from the

compartment a' into the body of the several sections around the ends or wings F² of the partitions F', and from thence it flows upward through the inner compartments a² 70 directly into the outflow-pipes. Within the water-jackets D⁸ D⁹, opposite each of the joints between the sections, are formed inclined cross-partitions G, extending not quite 75 to the bottom of the water-jacket to insure the circulation of the water in the water-jacket, as hereinafter explained. Projecting from the sections D' D² D³ D⁴ within the joints by which they are connected are lugs g', through 80 each adjacent pair of which bolts g² are passed, by which means the several sections are united. When being put together, the lowermost section D' is set in place and the bolts g' uniting the joints E' E² placed in position 85 through the openings in the upper side of the section D', and then the next section D² placed in position and the next set of bolts inserted, and so on throughout all the sections. In the upper side of the dome-section D⁴, opposite the joints E' E³, are formed hand-holes 90 H', through which the upper set of the bolts g² may be inserted and screwed up. These hand-holes will then be either provided with 95 covers or utilized, as shown in Fig. 1, to form means for connecting the overflow-piping H². The joints between the sections are formed as near the water-jackets D⁸ D⁹ as 100 convenient, and are flattened on their outer sides, as shown, so as to conform to the inner surface of the water-jacket sections and nearly meet the water-jackets at these points, so that these portions of the water-jackets are 105 protected by the joints from the direct influence of the fire, while at the same time the compartments a' in the sections D' D² D³ are likewise protected, so that the water therein 110 is kept cooler than in the other portions of the sections. In this connection also the partitions G perform an important function, as 115 being placed opposite the joints between the sections they confine the water in the cooler places opposite the joints of the sections, and thereby form conduits for the unobstructed flow of the cooler water downward into the 120 water-jackets, while the hotter water in the water-jacket sections on each side of the partitions (which parts are exposed to the direct influence of the fire) will flow upward, thus insuring a free and rapid circulation throughout the water-jacket sections. 125

As before mentioned, the joints or connections are so arranged as to protect the compartments a' from the direct influence of the heat, so that the water therein is kept from 130 boiling and at a less temperature than in the other parts of the generator. Hence the water will the more readily flow downward in the compartments a' (when used as a steam-generator) and replace the water rising 135 through the compartments a², and thus insure the requisite circulation of the water throughout all the sections.

The ash-pit A is provided with a door K',

adapted to rest, when closed, upon an inclined seat K^2 , and connected by chain or wire K^3 with an automatic damper-regulator K^4 of the usual construction. A trip-pawl K^8 is arranged to support the door K' in its open position, as shown, for the convenience of the operator in removing ashes and cinders; but to insure the closing of this door if it is accidentally left open the trip-pawl is connected by a chain or wire K^5 , leading over pulleys K^6 , and thence down to the short arm of the weighted lever K^7 of the regulator K^4 , as shown, so that any rise of the temperature which would elevate the diaphragm of the regulator and depress its short arm would draw the trip-pawl upward and release the door K' and allow it to close and thus shut off the draft. By this simple means, if the door is carelessly left open, as soon as the temperature rises to an extent sufficient to cause the regulator to act the trip-catch will be automatically released and the door closed, and thus avoid any abnormal increase of temperature which might result in an explosion.

The gradual inclining or curving upward of the upper surfaces or sides of the horizontal heating sections or parts, as well as the upper part of the fire-pot, and the gradual upward development of the same into conduits or compartments for the upward flow of the steam or heated water facilitates and accelerates the passage of the steam or heated water from the heating parts and its upward flow to the steam-dome or (in a hot-water generator) to the outflow-pipes, and thereby also diminishes the number and capacity of conduits necessary for the upward flow of the steam and hot water and prevents the pocketing or detention of steam-bubbles and endangering the burning out or destruction of the parts.

The connecting together of the sections of the generator by means of the lugs inclosed within the water-chamber of the same and bolting them together within such sections is also an important feature of my invention, as it renders it more convenient to connect the parts and facilitates the union of such parts, as well as making the connection more secure. It also permits the use of short bolts for connecting the several parts and so avoiding the greater expansion and contraction which would result from the use of longer bolts or rods.

The bolts and connecting parts, as before

stated, are also protected from the destructive action of the fire, and, being at all times immersed in the water, uniformity of temperature is maintained and equable and simultaneous expansion of the bolts with the other parts connected by them secured, so as to prevent leakage at the joints or rupture of the parts.

The partitions G in the jacket-sections, as before stated, are also an important feature, as they serve to conduct the return or supply water in the jackets and promote and direct the course of the circulation, so that the supply-currents will not oppose or conflict with the steam-bearing currents.

Drainage-tubes will be connected at suitable points into the lower edges of the jacket-sections.

Having thus described my invention, what I claim as new is—

1. In a steam or hot-water generator, a series of hollow sections, with alternately annular and solid surfaces around and through which the flame and other products of the combustion are adapted to pass, connections between said sections formed to incline upward from all points of the upper surfaces or sides of said sections, and cross-partitions F' within said connection and extending into the interior of said sections by outwardly-projecting wings F^2 , substantially as and for the purpose set forth.

2. In a steam or hot-water generator, one or more hollow sections alternating with one or more hollow sections of larger diameter and with central openings and having downward extensions forming a water-jacket encompassing said smaller sections, connections between said hollow sections in close proximity to said jacket-extensions, and partitions F' within said connections, and with wings F^2 extending into the interior of said sections, and with partitions G within said jacket-extensions, whereby a difference of temperature is secured within the generator to cause the requisite circulation of the water, substantially as and for the purpose set forth.

In testimony whereof I have hereunto set my hand in the presence of two subscribing witnesses.

DANIEL A. DICKINSON.
